US00D718659S

(12) **United States Design Patent**
Lin et al.

(10) **Patent No.:** US D718,659 S
(45) **Date of Patent:** ** Dec. 2, 2014

(54) **BUS**

(71) Applicant: **BYD Company Limited**, Shenzhen, Guangdong (CN)

(72) Inventors: **Shangqing Lin**, Shenzhen (CN); **Yuncheng Zhang**, Shenzhen (CN); **Xiaoming Zhong**, Shenzhen (CN); **Yubo Lian**, Shenzhen (CN); **Wang Peng**, Shenzhen (CN)

(73) Assignee: **BYD Company Limited**, Shenzhen, Guangdong (CN)

(**) Term: **14 Years**

(21) Appl. No.: **29/466,780**

(22) Filed: **Sep. 11, 2013**

(30) **Foreign Application Priority Data**

Mar. 12, 2013 (CN) 2013 3 0060331

(57) **CLAIM**

The ornamental design for a bus, as shown and described.

DESCRIPTION

FIG. 1 is an enlarged front left perspective view of a bus showing our new design;

FIG. 2 is an enlarged rear right perspective view thereof;

FIG. 3 is a front elevation view thereof;

FIG. 4 is a rear elevation view thereof;

FIG. 5 is a left side view thereof;

FIG. 6 is a right side view thereof; and,

FIG. 7 is a top plan view thereof.

The broken lines shown in the drawings illustrate portions of the bus that form no part of the claimed design.

1 Claim, 7 Drawing Sheets
